UNITED STATES PATENT OFFICE

FRANCIS W. SHEPHERD, OF SALT LAKE CITY, UTAH, ASSIGNOR OF ONE-HALF TO PERRY
A. CLARK, OF SALT LAKE CITY, UTAH

COOLING COIL

Application filed August 11, 1928. Serial No. 298,963.

My invention relates to the cooling of liquids such as beverages and has for its object to provide a new and efficient cooling coil that will maintain a constant low temperature for liquids or beverages suitable for all domestic and commercial purposes.

A further object is to provide a cooling coil for use with any type of refrigeration system for cooling liquid beverages, such as orange juice, root beer, near beer, and all carbonated drinks.

A still further object is to provide a cooling system for beverages which eliminates the danger of the refrigerant leaking through the coil into the beverage and one in which all connections are made outside of the beverage container.

A still further object is to provide a cooling system which will maintain a constant temperature longer and will cool off the incoming beverage quicker than has heretofore been accomplished, so that there will be a constant supply of cool beverage in the container at all times.

These objects I accomplish with the device illustrated in the accompanying drawings in which similar numerals and letters of reference indicate like parts throughout the several views and as described in the specification forming a part of this application and pointed out in the appended claims.

In the drawings in which I have shown the best and most preferred manner of building my invention Figure 1 is a side elevation of my invention with parts of the container shown in dotted lines. Figure 2 is a section of the cover plate and the upper portion of my coil showing the connecting means employed to connect the coils to the cover and the inlet and outlet pipes.

In the drawings in which I have shown the container in which my cooling coils are mounted as A, having an opening in the top end thereof over which the cover plate B of my device is placed and secured by the bolts 1. Centrally on the lower side of the said cover plate I provide a cylindrical casing 2, having a filler plug 3 through the cover plate B through which fluids may be passed.

To one side of the said casing and in open connection therewith I secure one end of a large coil 5, made by bending a pipe 6 into a spiral coil with one end of the said spiral coiled pipe 6 bent upwardly along one inner side of the said coil to the cover B, where it is secured therethrough with the opening in the end of the said pipe 7 closed, and centrally perforated. Centrally within the said casing 2 I provide another and smaller casing which is termed an accumulator pot 10, which pot is suspended therein by a small pipe 14. A smaller coiled pipe 11 of smaller diameter than the pipe 6 is placed within the said pipe 6 being surrounded thereby and one end of the said pipe 11 is secured to the said pot 10 in open connection therewith and the other end 11a is brought upwardly through the end 7 of the pipe 6 and out through the perforated end of the said pipe 7, and in the free end thereof I provide a control valve 13, to control the flow of liquid through the pipe and coil, and into the pot 10. An outlet pipe 14 is then secured to the top side of the said pot 10 and in open connection therewith, and the free end of the said pipe 14 is passed up through the cover plate B and is secured thereto by suitable means. I then provide a bracket 8 on the bottom end of the pot 10 and this bracket under the pot with the pipe 14 support the pot 10 within the casing 2. The outer free end of the said pipe 14 is provided with a valve 15 to control the flow of liquid therefrom. Both valves 13 and 15 are provided so that the entire assembly may be properly charged and tested on the bench of the manufacturing company before it is installed in the beverage container.

The accumulator pot is for the purpose of trapping any liquid from the coil 11 to prevent and insure that only gas is drawn back from the system into the compressor of the refrigerating system to which my invention is connected, and also to add to the cooling capacity of the entire machine. It also acts as a receiver and reserve capacity for the refrigerant, to insure sufficient volume of refrigerant for the best results and to eliminate

the necessity of an accurate charge and frequent service.

The modification shown in Figure 3 of the drawings shows the accumulator pot 10 lengthened and the casing 2 lengthened to near the bottom of the coil 5 and in this modification I extend the pipe 11 and bend it downwardly to near the bottom of the casing 2 and then form it into a coil 11b around the outer 10 surface of the accumulator pot 10 and the top end of the coil 11b is then introduced into the pot 10 near the top end thereof. This construction enables me to have a greater cooling surface around the pot 10 and within the casing 15 2 thereby giving greater efficiency to the device where different forms of the device are desired and where greater cooling is necessary.

The operation of my device is as follows:

20 Glycerine or some other nonfreezing solution is introduced into the casing 2 through the plug 3, and the casing and coil 5 are filled, with allowance made for expansion and contraction. The control valve 13 is connected 25 with the inlet end of a refrigerating system and the valve 15 is connected with the outlet end making a complete circuit through the valve 13, down through the pipe 11a and up through the coil pipe 11, the pot 10 and out 30 through the pipe 14 and the valve 15, back to the system.

It will be obvious that the inlet and outlet 35 pipes of the system might be mounted through the side walls of a container rather than through the top without departing from the spirit of the invention or the scope of the claims.

Having thus described my invention I desire to secure by Letters Patent and claim:

40 1. In a cooling system for beverages the combination of a cover plate, a casing secured on the inner side thereof; a coil having one end secured in open connection with said casing and the other end bent upwardly and secured to the cover plate; another casing secured within said first mentioned casing; a coil of pipe of smaller diameter than the first mentioned coil carried therein and having one end secured to said last mentioned 45 casing above the bottom thereof and the other end passed upwardly and out through the top end of said first mentioned coil; a pipe connecting said second mentioned casing with the outlet pipe of a refrigerating system; a 50 valve in said connection to control the flow of liquid therethrough; and another valve connecting the refrigerating system with the free end of said inner coil.

55 2. In a refrigerating system for beverages the combination of a coil within a coil with one end of the outer coil closed and the other end secured to a casing; an accumulator pot within the casing and with the top portion thereof in open connection with one end of 60 said inner coil; a pipe connecting the top of

70 said pot with a refrigerating system; a valve connecting the free end of the said inner coil with the other lead line of the refrigerating system; and valves to control the flow of refrigerant to and from said inner coil.

75 3. In a cooling system for beverages the combination of mounting a casing on the under side of the cover of the beverage container; an accumulator pot secured within said casing; a large coil having one end closed and the other end secured to and in open connection with said casing; a smaller coil carried in said large coil and having one end secured to the upper portion of said pot and the other end secured through the cover; a pipe connected through the top of said cover and to said pot; and valves to control the flow of refrigerant into, through and out of said inner coil.

80 85 In testimony whereof I have affixed my signature.

FRANCIS W. SHEPHERD.
